UNITED STATES PATENT OFFICE.

WALTER J. RICHARDS, OF NORWOOD, OHIO, ASSIGNOR TO ALLIS-CHALMERS COMPANY, A CORPORATION OF NEW JERSEY.

VENTILATED LAMINATED CORE FOR DYNAMO-ELECTRIC MACHINES.

No. 890,577.

Specification of Letters Patent.

Patented June 9, 1908.

Application filed October 31, 1906. Serial No. 341,374.

To all whom it may concern:

Be it known that I, WALTER J. RICHARDS, a citizen of the United States, residing at Norwood, in the county of Hamilton and State of Ohio, have invented certain new and useful Improvements in Ventilated Laminated Cores for Dynamo-Electric Machines, of which the following is a full, clear, and exact specification.

10 My invention relates to electric machines or apparatus and particularly to ventilated laminated cores.

It is customary to provide transverse or radial ventilating passageways at intervals 15 in laminated cores by spacing the laminae apart by brass separators in the form of skeleton rings or segments. It is essential that the ribs of the separators be thin so as to interfere as little as possible with the proper 20 circulation of the cooling air currents. These brass separators are therefore difficult to cast, and expensive, and in cores of large diameter having separators consisting of a large number of segments, considerable time 25 and labor is required to match and assemble the segments.

The object of my invention is to dispense with the separators heretofore employed and still obtain sufficient ventilation through the 30 cores.

In carrying out my invention, I provide transverse or radial ventilating passageways in a core built up entirely of flat laminae.

More specifically considered my invention 35 consists in a core for dynamo-electric machines comprising main laminae and groups of special ventilating laminae arranged at intervals between the main laminae, the special ventilating laminae having over- 40 lapping openings through which air may pass.

My invention still further comprises certain details of construction and combinations and arrangements of parts described in the specification and set forth in the 45 appended claims.

For a better understanding of my invention reference is had to the accompanying drawings forming a part of this application, in which

50 Figure 1 is a partial longitudinal section through a machine equipped with my invention; Fig. 2 is a section through the armature core, the section being taken along the line 2—2 of Fig. 1 looking in the direction 55 of the arrow; Fig. 3 is a partial elevation of

one of the special ventilating laminae; Fig. 4 is a similar view of a slight modification of the same; Fig. 5 is a similar view of a second special ventilating lamina employed in conjunction with the lamina shown in Fig. 3 or 60 Fig. 4; Fig. 6 is a similar view of one of the main laminae of the core; Fig. 7 is a partial longitudinal section through a rotor having a core constructed according to my invention, mounted on a spider; Fig. 8 is a partial 65 transverse section of the same along the line 8—8 of Fig. 7, looking in the direction of the arrow; Fig. 9 is a partial longitudinal section through a stator core equipped with my invention; and Fig. 10 is a partial trans- 70 verse section along the line 10—10 of Fig. 9, looking in the direction of the arrow.

My invention may be applied to cores of any diameter, built up of either circular disks or segments, or to either rotary or sta- 75 tionary cores.

In all modifications of my invention, for each ventilating passageway, I employ two special forms or kinds of laminae arranged in two or more groups, which are preferably 80 adjacent one another, one group or groups of the laminae having openings or slots open at the periphery of the core and the other group or groups having openings or slots which overlap the openings or slots in the first men- 85 tioned group or groups and which are either open at the opposite periphery of the core or communicate with longitudinal passageways open at the ends of the machine.

Reference is first had to Figs. 1 to 6 of 90 which Figs. 1 and 2 show a machine of small size having an armature core built up of laminae in the form of disks mounted directly on the shaft and of which Figs. 3 to 6 show portions of the laminae adapted to be em- 95 ployed therein. At 10 is shown an armature shaft on which is mounted an armature 11 and commutator 12. Surrounding the armature is a stationary field member having field poles, one of which is shown at 13. The 100 laminae of the armature are clamped between end-members 14 and 15, the former of which bears against a shoulder 16 on the shaft and the latter of which bears against a clamping ring 17. The core is slotted in the 105 usual manner and carries an armature winding connected to the bars of the commutator. It is to be understood however that my invention is applicable to alternating current machines as well as to direct current ma- 110

chines. My improved laminated core consists of three different kinds of punchings or laminæ; *i. e.* main laminæ 18, special ventilating laminæ 19, and special ventilating laminæ 20. The main laminæ 18 form the largest portion of the core. These laminæ, one of which is shown in Fig. 6, are of the usual shape. They are provided with peripheral slots 21, to receive the armature conductors, teeth 22, ventilating openings 23, and a shaft opening 24. The ventilating laminæ are arranged between the main laminæ at one or more points so as to form radial or transverse ventilating passageways or spaces. For each transverse ventilating passageway there are one or more groups of laminæ 19 and one or more adjacent groups of laminæ 20. In Fig. 1, I have shown for each ventilating passageway two groups of laminæ 19 and an intermediate group of laminæ 20. Each lamina 19 is provided at its periphery with slots and teeth the same as the main laminæ, and with a number of openings or slots 25 which communicate with the openings 23 and extend outward toward the periphery of the lamina, the slots being separated by radial fingers 26. These openings 25 may be open at the inner periphery of the lamina as is shown in Figs. 1 and 3 or may be closed. The latter form is shown in Fig. 4, the lamina 19^a having closed openings or slots 25^a which serve the same purpose as the openings or slots 25 in lamina 19. The laminæ 19 provide greater heat radiating surface but the long teeth 26 may be bent or twisted. The latter objection is overcome with the form of lamina shown in Fig. 4. In larger machines, however, in which a circulation of air is desired directly through the core from one periphery to the other, the slots must be open. The ventilating laminæ 20, one of which is shown in Fig. 5, adjacent the laminæ 19 are provided at their outer peripheries with slots 27 deeper and wider than the slots 21 in the other laminæ, and with long and narrow teeth 28 of the same number as the teeth in the other laminæ. The body of each lamina 20 is similar to the body of the main laminæ 18, having ventilating openings 23 which communicate with the ventilating openings in the main laminæ. The depth of the slots or openings 27 is such that, when the laminæ are assembled, the slots 27 in laminæ 20 overlap the slots or openings 25 or 25^a in the laminæ 19 or 19^a. The ventilating openings 23 in the disks form the usual longitudinal ventilating openings 29 through the core, the end-members being provided with openings which permit air to be drawn into the machine.

By referring to Figs. 1 and 2, it is seen that when the machine is in operation air is drawn into the longitudinal passageways 29, and passes first to the openings 25 in laminae 19, then into the overlapping openings 27 in

laminæ 20, and out of the machine through the openings between the teeth 28 and the conductors in the slots 21.

The number of ventilating laminæ in each group may be varied at will and depends generally on the size of the machine or the volume of air required. Also the relative arrangements of the ventilating laminæ may be varied. For example there may be for each ventilating passageway, a single group of laminæ 19 between two groups of laminæ 20, or a single group of laminæ 19 and a single group of laminæ 20, as will appear from the following description and illustration. It is not necessary that the two groups of special ventilating laminæ be adjacent, but all that is necessary is that the openings in one group communicate with the openings in another. Accordingly the two groups of laminæ may be separated by other laminæ having openings to permit the air to pass from the openings in one group to the openings in the other.

Referring to Figs. 7 and 8, it is seen that I have shown my invention applied to a larger type of machine. In this case the core is built up of segments of laminæ which are dove-tailed to the arms of a spider 30. There are three forms of segments—main segments 31, and ventilating segments 32 and 33. The ventilating segments 32 have openings or passageways 34 which correspond with openings 25 or 25^a of the disk laminæ 19 or 19^a first described, and segments 33 have openings 35 which correspond with the openings or slots 27 in disk-laminae 20. In this case, I have for each transverse ventilating passageway two groups of segments 33 and an intermediate group of segments 32. With this arrangement, air passes from the longitudinal passageways 36 into the openings or slots 34 of segments 32, then into the openings or slots 35 in the two groups of segments 33, and then out of the core at its outer periphery. If desired the openings or slots 34 may be open at the inner periphery of the core between the arms of the spider so that air may pass directly through the core from the inner to the outer periphery.

In Figs. 9 and 10 I have shown a portion of a stator core equipped with my invention. In this case, the laminæ of the core are built up of segments dove-tailed to the outer surrounding stator frame 37. As in the preceding cases the core consists of main segments 38 of laminæ 38 of the ordinary form, and groups of the special ventilating segments of laminæ 39 and 40 arranged at intervals between the main segments. The segments 39 have openings or slots 41 which are open at the outer periphery of the core and the adjacent segments 40 have openings or slots 42 which overlap the slots 41 and which are open at the inner periphery of the core. It is seen that air will be forced by the rotor

into the openings 42 of segments 40 then into openings 41 of segments 39, and then out through the stator frame. In this case I have shown only a single group of segments 5 39 and a single group of segments 40 for each transverse ventilating passageway. If desired, however, different arrangements as shown in the preceding figures may be employed.

10 It is apparent that I have provided means for securing good ventilation through the cores of machines of any type without employing spacing means heretofore employed, but the ventilating air currents pass entirely 15 through flux carrying laminæ. It is also apparent that the different forms and arrangements of the special ventilating laminæ may be widely varied.

While I have shown several of the forms 20 and applications of my invention I do not wish to be confined to the same as it may have a wider application and may be embodied in different forms than here shown.

I aim in my claims to cover all modifications which do not involve a departure from 25 the spirit and scope of my invention.

What I claim as new and desire to secure by Letters Patent is:—

1. A core for dynamo-electric machines 30 comprising a plurality of main laminæ and groups of special laminæ arranged at intervals forming ventilating passageways, the special laminæ having overlapping openings 35 adjacent respectively the outer and inner peripheries of the core.

2. In a laminated core for dynamo-electric machines, a plurality of main toothed laminæ and a group of adjacent flat laminæ having teeth longer and narrower than the

teeth of the core so as to form deep slots at 40 the periphery of the core, said core being provided with ventilating passageways communicating with said deep slots.

3. In a toothed laminated core for dynamo-electric machines, a plurality of main 45 laminæ slotted to receive conductors, and a group of adjacent laminæ having slots deeper and wider than the slots of the main laminæ, said core being provided with axial ventilating passageways and other passageways 50 connecting said axial passageways with said deep slots.

4. A core for dynamo-electric machines; comprising main laminæ slotted to receive conductors, and special laminæ formed to 55 permit ventilation, said special laminæ comprising a group of laminæ having slots within the body of the core and slotted at the periphery to receive conductors, and a group of laminæ having slots extending inward 60 from the periphery and over-lapping the slots of the other special laminæ.

5. A core for dynamo-electric machines comprising main laminæ slotted to receive conductors, a group of special laminæ having 65 deeper slots and narrower teeth than the main laminæ, and a group of laminæ slotted to receive armature conductors and having slots in the body of the core and overlapping the deep slots of the first group of special 70 laminæ.

In testimony whereof I affix my signature, in the presence of two witnesses.

WALTER J. RICHARDS.
